[57] CLAIM

The ornamental design for a portable handset radio telephone, as shown and described.

DESCRIPTION

FIGS. 1 and 2 are respectively front and rear elevational views of a portable handset radio telephone showing my new design in closed position;

FIGS. 3 and 4 are respectively left and right side elevational views thereof;

FIGS. 5 and 6 are respectively top and bottom plan views thereof;

FIG. 7 is a cross sectional view taken on line VII—VII in FIG. 4, with interior construction shown;

FIG. 8 is a front, top and right side perspective view thereof;

FIG. 9 is a right side elevational view thereof in opened, operative position; and

FIG. 10 is a front, top and right side perspective view of a second embodiment thereof, in opened, operative position, the differences of this embodiment vis-a-vis the first embodiment as shown in FIG. 9 being (1) display of the antenna extended, and (2) showing of the large display panel and sundry pushbutton tops with conventional letters, numerals, words and symbols of in-service nature.
